BELLOWS FOLDING MACHINE

Clare B. Rowland and Owen A. Christensen, Flint,
Mich., assignors to General Motors Corporation,
Detroit, Mich., a corporation of Delaware

Application November 4, 1948, Serial No. 58,262

26 Claims. (Cl. 93—1)

1 This invention relates to machines for folding sheet material, and more particularly for folding a tube of sheet material into a bellows.

The object of the invention is to fold a long tube of sheet material rapidly and accurately into a polygonal bellows.

Another object of the invention is to provide a bellows folding machine having a series of folding hinges for each side of the bellows in which aligned groups of folding hinges will act in sequence to form the folds of a polygonal bellows.

Another object of the invention is to provide clamping and securing means to hold and seal the ends of the tubular sheet material so that air under pressure may be maintained in the tube to hold the sheet material in contact with the folding hinges of the machine during the folding operation.

Another object of the invention is to provide a polygonal bellows folding machine in which a plurality of series of folding hinges contact a substantial area of the tubular blank in forming the bellows and contact all the area of the tubular blank of the completed polygonal bellows.

Another object of the invention is to provide a polygonal bellows folding machine consisting of a plurality of similar series of slidably mounted folding hinges. Each series, which has a multiplicity of slidably mounted folding hinges, may be increased in length by adding more folding hinges in order to produce a longer bellows.

Further objects and advantages of the invention will be apparent from the following description of specific embodiments illustrated in the drawing, in which—

Figure 1 is a vertical elevation with certain parts broken away.

Figure 2 is a horizontal elevation along the line 2—2 of Figure 1 with certain parts broken away.

Figure 3 is an end elevation in partial section taken along the line 3—3 of Figure 1 with certain parts broken away.

Figure 4 is an enlarged perspective view of a fold plate.

Figure 5 is an enlarged fragmentary vertical section with certain parts broken away and shown in section.

Figure 6 is a fragmentary view of a portion of Figure 5 showing the fold plates in the expanded position.

Figure 7 is a fragmentary view of a portion of Figure 5 showing the fold plates in the compressed position.

Figure 8 is an exploded perspective view showing the details and relative position of the sliding blocks.

2 Figure 9 is a fragmentary enlarged cross sectional view.

Figure 10 is a perspective view of a partially folded bellows.

The bellows is folded from a tube in accordance with this invention by internally supporting the tube with compressed air and forming the folds or pleats successively with a plurality of series of folding hinges or hinged fold plates. In forming an octagonal prismatic bellows as shown in Figure 10 with four longitudinal series of pleats, four longitudinal series of folding hinges are employed. Each series has a number of folding hinges to form the desired number of pleats. It will be noted that the opposite pairs of pleats are in transverse alignment but that one pair is longitudinally offset with regard to the other pair. The fold plates are then successively folded inwardly to form the pleats. Polygonal bellows having more than eight sides may be made by employing more than four longitudinal series of fold plates. A dodecagonal prismatic bellows may be made by employing six longitudinal series of fold plates with the plates of three alternately located longitudinal series longitudinally displaced from the remaining three longitudinal series.

Referring to the drawings, the bellows folding machine is mounted and secured on a suitable base 10 positioned on the supporting frame 11. The base 10 and frame 11 and other parts of the machine are secured together by suitable means such as screws, bolts or welding, etc. A bottom plate 12 and a pair of bottom guides 13 positioned along each edge of the bottom plate are secured to the base 10. A guide slot 14 is formed by a recess at each longitudinal edge of the bottom plate 12 and the side of the bottom guides 13 to guide the side blocks 16. The side folding hinges 17 are pivoted to side blocks 16. The guides 13 have grooves 18 to guide the bottom blocks 20 which support the bottom series of folding hinges 17.

A series of cover supports 25 are mounted on the base 10 have a boss 24 engaging the cover guides 29 to support the cover assembly. The upwardly extending guide members 26 are secured to some of the supports and have a bevelled end to transversely guide and position the cover 27. In order to laterally guide and position the cover end guides 23 with a similar bevelled end are secured to the sides of the end supports 25. Latches 30 are mounted on the other supports to provide a means to lock the cover in position as described below.

In Figures 1 to 3 the cover 27 is shown in full lines in the raised or opened position, while in

3

Figure 3 the dot-and-dash lines show the cover in the closed operating position. The supports 25 are recessed to fit flush with the inner edge of the guides 13 and are secured to the base.

A top plate 28 similar to bottom plate 12 is secured on the under side of the cover and a pair of top guides 29 are secured to the cover along the side edges of the top plate. A pair of guide slots 31 for the upper ends of the side blocks 16 are provided by a recess along each edge of the top plate and the adjacent side of the top guides. An elongated longitudinal top groove 32 is provided in the inner side of the top guides 29 to hold the top blocks 33 which support the top series of folding hinges 17.

In order to facilitate movement of the cover assembly from the open position to the closed position shown in dot-and-dash lines in Figure 3, the cover is counterweighted. A pair of pulleys or gears 36 are fixed to a shaft 37 suitably supported above the cover by means, such as posts 38 mounted on the supporting frame 11. A pair of chains 39 extend over the gears 36 and are attached at one end to the cover 27 by the link 41 and at the other end to the counter-weight 42. The gears 36 are fixed to the shaft 37 to maintain the cover in horizontal position.

A locking mechanism is mounted on the cover to lock it in either opened or closed position. The lock mechanism is operated by a handle 44 fixed in the trunnion 45 which is pivotally mounted on the cover 27. A pair of discs 46 are secured to the trunnion in spaced relation to operate similar toggle locks at each end of the cover. One end of each connecting link 47 is pivotally connected between the discs 46 on opposite sides of the trunnion 45. The other end of each link 47 is pivoted to a rod 48 reciprocally mounted in guides 49 which are fixed to the cover. Each rod 48 is pivotally connected to toggle links 52 and 53. Each toggle link is pivotally connected to a locking bolt 54 which is reciprocally mounted in guide 55. Thus it will be seen that there is one locking bolt 54 adjacent each corner of the cover, and that all the bolts are simultaneously operated by the centrally located handle 44.

In order to secure the cover in open position the lock bolts 54 engage latches 57 suitably mounted above the machine and supported on arms 58 fixed to the posts 38. As the cover 27 is lowered it is guided by plate 59 fixed on post 38 and will pass between the lower latches 60. Then the bolts 54 may be extended to lock the cover in closed position. In order to guide the cover into either end position the ends of the upper and lower latches 57 and 60 are bevelled and are spaced slightly further apart than the width of the cover 27. The final positioning of the cover occurs when the guides 29 engage the inner edge of the guide portion 26 of the supports and rest on the supports 25.

The four longitudinal series of folding hinges 17 which form the pleats in the tube to form the bellows extend substantially throughout the length of the machine. Since all the folding hinges are the same and the mounting blocks in each series are the same, the details are shown in Figures 4, 5, 8 and 9 which illustrate a section of each series.

Referring to Figure 9, which shows a cross section of the slide blocks and fold plates with the cover 27 in closed position, it will be seen that the top guides 29 with the top plate therebetween and the bottom guides 13 with the bottom plate therebetween form an elongated frame having a

square cross section. A series of slide blocks 16 are located at each side of this frame with the upper end in guide slot 31 and the lower end in guide slot 14. The blocks 16 on opposite sides of the frame face each other and are intransverse alignment. Between each side block 16 is positioned at the bottom a bottom guide block 20 and at the top a top guide block 33.

The folding hinges 17 as shown in Figure 4 are trapezoidal in shape and have conventional pintle journals 61 on the short base of the trapezoid and pintle journal 62 on the long base of the trapezoid. A pair of folding hinges 17 are hinged together by passing a short pintle 63 through the short journals. As shown in Figure 9 the short pintle 63 extends at each end beyond the journals 61 and enters the eye of the studs 64 to secure the folding hinges to the side slide blocks 16. A folding hinge 17 will then extend from each slide block 16 toward the adjacent slide block on the same side. The long journals 62 on the long trapezoidal base mate and are hinged together by the long pintle 65. The whole series of slide blocks 16 on each side are thus connected together by the folding hinges 17.

Similarly folding hinges 17 are hinged by pintles 63 and studs 64 to the bottom blocks 20 and top blocks 33. The bottom and top folding hinges are also hinged together in a continuous series by long pintles 65.

The ends of the slide blocks overlap and thus must have interfitting recesses so that they may be moved together to move the hinges inwardly to form the pleats. As best shown in Figure 8 the side slide blocks 16 have recesses 68 adjacent the base which interfit with recesses 69 adjacent each end of the bottom slide block 20, so that both the side blocks 16 and the bottom blocks 20 can be moved together until the side faces contact. The top slide block 33 has recesses 71 at each end similar to recesses 69. The top end of the side blocks 16 have open recesses 72 on each side. These recesses similarly enable the side block and the top blocks to be moved together. The recesses 72 are opened to allow the top block 33 which is mounted in the cover 27 to be removed with the cover.

The ends of the long pintle 65 pivoting the hinges 17 mounted on the side blocks 16 extends into a slot 74 in the bottom block 20 and a slot 75 in the top block 33. The slot 75 has bevelled edges to correct any misalignment of the long pintle 65 and the top block 33 when the cover is placed on the machine. The side blocks 16 also have centrally located slots 76 to provide a guide for the ends of the pintles 65 of the hinge series mounted on both the top blocks 33 and the bottom blocks 20. The top ends of the slots 76 in the side blocks 16 are bevelled both laterally and transversely to correct any misalignment when the cover is positioned.

In order to move the blocks from the closed position to the opened position each of the side slide blocks 16 has a leaf spring 78, as best shown in Figure 5 attached in a slot 79 in each side edge of the side blocks 16. The leaf spring 78 has a central bight 80 that engages and is secured by a pin 81 passing through an aperture in the block. Similar slots 83 and 84 are formed in each side edge of the bottom block 20 and the top block 33 respectively to provide a space for springs 78 secured in the same manner by a pin 81 extending through an aperture in the blocks. The springs 78 extending from adjacent sides of each pair of

adjacent blocks abut at the ends. Thus the springs are compressed when the folding hinges are moved to closed position and assist in moving the folding hinges and blocks toward opened position. The pins 81 have an enlarged head or stop 82 which limits the outward movement of the folding hinges 17 to prevent the hinges from going over dead center and locking in the opened position. The springs shown at the outer side of the side end blocks may be omitted.

As shown in Figure 2 at the fixed end of the machine, a top abutment block 86 is attached to the top plate 28, or retained in the guide grooves 32 by the end plate 91, to provide a stop for the last pair of side blocks 16. The abutment block 86 has a recess 87 at each end which interengages with the recesses 72 on the last pair of oppositely disposed side blocks 16. A similar lower abutment block 88, as best shown in Figure 5, has similar recesses at each end to interengage with the recesses 68 at the lower end of the side blocks 16. The abutment blocks 86 and 88 are about one-half the width of the other blocks, and thus do not have the pintle supporting studs 64 employed on the full-width blocks. The end fold plate 17 at the fixed end of the bottom series is connected to a pintle support 90 which is secured to the outside of the end plate 93, as best shown in Figure 5. The support 90 is as wide as the short end of a fold plate and has a lateral journal portion 99 extending through an aperture in the end plate 93. The journal portion 99 terminates in two pivotal support journals similar to the journals on the short side of the trapezoidal hinge plates 17. The pintle journals on portion 99 are interfit with the pintle journals 61 on the last hinge 17 and are pivotally secured together by a short pintle 63. The bottom end plate 93 is suitably recessed above the aperture to provide clearance for the last hinge plate 17. The top pintle support 89, though not shown in detail, extends downwardly and is secured to plate 91, and a lateral pintle support extends through an aperture in the top end plate 91 to be pivotally connected with the top end folding hinge.

At the fixed end of the machine a top end plate 91 is attached to the cover 27 and has a central semi-circular cut-out 92, as shown in Figure 3. A similar lower end plate 93 is attached to the end of the bottom plate and has a similar central semi-circular cut-out 94. When the cover is in closed position the top end plate 91 and lower end plate 93 meet at their cut-out edges, and the top cut-out 92 and the lower cut-out 94 meet to form a circular opening. The edge of this circular opening is bevelled outwardly as shown in Figure 5 to receive the fixed end of the paper tube 126 and to provide an abutment for the tubular clamping jaw 95 which has a mating bevelled front edge.

The clamping jaw 95 is slidably mounted on one end of the air induction tube 96, which is supported at the other end in fixed position by tube support 97 mounted on base 10. The clamping jaw 95, with the one end of the induction tube 96 slidably mounted therein, is slidably supported by a journal 98. The clamping jaw 95 is reciprocated in the journal 98 by a cam and rotation is prevented by the pin 101 in the journal and the slot 102 in the clamping jaw. The rear edge of the tubular clamping jaw 95 has a cam surface 103 which engages a tubular cam 104. The tubular cam has an operating handle 106, and preferably abuts on the ring bearing 107 which is clamped on the air induction tube 75

96, though it will be noted that it could abut on the support 97. When the cam 104 is rotated it will move the clamping jaw 95 toward the end plates 93 and 91 to clamp the paper tube 126. When the cam 104 is returned to the opened position the clamping jaw will be returned by a spring 108 (Figure 5) located in a bore in the journal 98 and acting on a rod 109 which engages an abutment 110 on the clamping jaw. Two sets of spring-actuated return rods are shown in Figure 2.

At the movable end of the series of fold plates the end bottom block 20 has a pair of ears 115 which are apertured to receive a screw 116 to secure the end block to the head 117. The head 117 has a spacer 118 on which is mounted a sponge rubber bushing 119, which may fit into the end of the paper tube but preferably abuts the end of the tube, as shown in Figure 5. The head 117 is secured at the bottom to a guide plate 120 which slides in the grooves 18 on the bottom guides 13 in order to maintain the central position of the head. The upper face portion of the head 117 abuts the end top block. Thus the head 117 will move both the end top block 33 and the end bottom block 20 which will, in turn, transmit the movement to the end side blocks 16 and to adjacent top and bottom blocks through springs 78. The spacer 118 is made substantially as wide as the head 117, and is the proper thickness to engage the side blocks 16 when the hinges are folded completely inward as shown in Figure 7. The spacer 118 is cut away at both the top and bottom to provide clearance for the folding hinges. The head 117 is connected by piston rod 121 to a suitable source of power such as a hydraulic piston (not shown).

In forming a bellows with this folding machine the paper is first rolled or formed into a tube and sealed and cut off to the proper length. Then the machine with all of the fold plates in their fully extended position as shown in Figure 6, is opened as shown in Figure 1 by raising the cover and locking it in the raised position. Then the tube 126 is placed within the machine where it rests on the bottom series of folding hinges 17 and is confined by the side series folding hinges 11. Then the cover 27 is unlocked and lowered, so that the top guides 29 rest on the supports 25, and the side guides 26 and end guides 23 position the cover. Then the cover is locked by rotating the handle 44 to position the bolts 54 in the latches 60. The tube of sheet material should extend just through the aperture formed by the end plates 93 and 91.

Then the handle 106 is moved to rotate cam 104 and clamping jaw 95 to grip the tube between the clamping jaw and the end plates. Figure 5 shows the lower end plate 93 and the clamping jaw 95 gripping the tube 126.

Then air under pressure is supplied through the inductor tube 96 to hold the paper tube 126 against the folding hinges 17, and the head 117 is moved to the left by the power source. The head 117 is secured to the first bottom block 20, and engages the first top block 33 in the open position shown in Figure 6, with the hinge plates 17 abutting the stops 82 to prevent locking. The hinge plates between each pair of blocks at the top and bottom are hinged at the center by a long pintle 65 which extends into the slots 76 in the intermediate side block and maintains this block midway between the top and bottom blocks. Similarly the top and bottom blocks are

7

maintained midway between the bottom blocks. This interlocking arrangement of the top and bottom and the side blocks determines the relative movement of the blocks and hinges. When the head 117 starts to move the first top and bottom end blocks, the first pair of side blocks will move at half speed and the second pair of top and bottom blocks will move at quarter speed. Theoretically each successive pair of blocks will move at one-half the speed of the preceding pair of blocks. However, due to the necessary clearance between the parts this movement diminishes more rapidly and is not noticeable after the fifth to tenth block. When the bottom and top blocks engage the side blocks at the bottom of slots 68 and the head spacer 118 engages the side blocks, they will move at the same speed as the head and transfer the movement in the same manner to successive blocks. Thus the blocks will move together progressively in a wave. Since the blocks are moved by force transmitted through the hinges 17 and the long pintles 65, springs 18 are inserted between the blocks to transmit some force from block to block before the blocks are in actual contact, and thus remove some of the load from pintles 65. Thus as the head moves toward the fixed end of the machine, the top and bottom hinges and then the side hinges will move together alternately and progressively in a wave formation to pleat the paper tube 126. When all of the folding hinges are in the completely closed position as shown in Figure 7, the tube will be formed into a bellows as shown in Figure 10. The air supply is stopped.

Then the cover 21 is unlocked and raised to open the machine and the head 117 is returned by the power cylinder to the opened position. The tube which is creased to form a bellows but in elongated form is removed.

The return movement of the head 117 will draw the folding hinges 17 mounted on the side blocks 16 and the bottom blocks 20 to the opened position due to the fact that the last bottom block 20 is secured by screw 116 to the head. However, when springs are located between these side and bottom they will return the folding hinges with substantially no load on the head 117. The springs between the top blocks 33 are preferably made strong enough to return the block to opened position. Thus the top folding hinges will return to the opened position when the cover is raised, and thus the cover can be raised before the head is returned to the opened position without requiring a hand operation to return the top series of fold plates.

The above described specific embodiment is illustrative of the invention. Other modifications within the terms of the appended claims will be apparent to those skilled in the art.

We claim:

1. In a machine of the character described, a frame, means to supply compressed air to the interior of a tubular blank, sealing means secured on said frame to clamp one end of the blank, sealing means slidably mounted on the frame to seal the other end of the blank, a plurality of series of folding members arranged about said tube, the folding members of each series being hinged together, a plurality of slide blocks mounted in said frame, alternate hinges between said members being pivoted to said blocks, means to move said blocks and slidably mounted sealing means toward the other sealing means to form said tube into a bellows.

2. In a machine of the character described, a

prism-shaped frame, means adjacent one end of the frame to supply compressed air to the interior of a tubular blank, means fixed to said frame to seal one end of the blank, means slidably mounted on said frame to seal the other end of the blank, a series of blocks slidably mounted on each side face of said prism-shaped frame, a folding plate pivotally mounted on each slide block, said folding plates mounted on adjacent blocks of each series being hinged together, means to move each block toward the fixed means whereby said folding plates move inwardly to fold said tubular blank into a polygonal bellows.

3. In a bellows folding machine, a supporting frame, means mounted on the machine axis on said supporting frame to clamp one end of a tubular bellows blank, means mounted on the machine axis on said supporting frame to seal the other end of the tubular blank, means to supply air under pressure through said clamping means to said tubular blank, a plurality of series of hinged fold plates positioned about said axis and each series extending along said axis, said fold plates being movable inwardly toward said axis to form said tube, a plurality of series of blocks supported on said supporting frame for longitudinal sliding movement, and each fold plate being pivotally mounted on one of said blocks.

4. In a machine of the character described, a supporting frame, fixed sealing means mounted on said supporting frame to secure one end of a tubular blank, a movable sealing means mounted on said supporting frame and sealing the other end of said blank, means to admit compressed air to the interior of the tube through one of said sealing means, a plurality of series of folding members having straight edges, the adjacent straight edges of the folding members of each series being hinged together, alternate series of said folding members having the straight edges engaging the paper spaced between the straight edges of the intermediate series, means mounted on said supporting frame to guide said folding members and means to move said folding members inwardly in sequence commencing with the end alternate folding members and then the adjacent intermediate folding members, and said folding members at the same time moving longitudinally toward the fixed sealing means.

5. In a machine of the character described, a prism-shaped frame having a plurality of fixed longitudinally extending faces, means adjacent one end of the frame to supply compressed air to the interior of a tubular blank, means fixed to said frame to seal one end of the blank, means slidably mounted on said frame to seal the other end of the blank, a series of slide blocks longitudinally slidably mounted in fixed lateral relation to each side face of said prism-shaped frame, a folding plate mounted on each slide block, means to move each folding plate inwardly to fold said tubular blank into a polygonal bellows.

6. In a machine of the character described, means to internally support a tubular bellows blank, a fixed prism-shaped frame having a plurality of longitudinal side faces surrounding said blank, a series of blocks mounted for longitudinal sliding movement along each side face of said prism-shaped frame, a fold plate pivotally mounted on each block, means to move said blocks with straight longitudinal movement and in fixed lateral relation to the frame toward one end of the frame, and means responsive to longitudinal movement of said blocks to move said plates toward each other to fold said tube into a bellows.

7. In a machine of the character described, a supporting frame, means to internally support a tubular bellows blank, a plurality of series of fold plates positioned to form a tunnel surrounding the tubular bellows blank, hinge means pivotally connecting adjacent pairs of said plates together, said hinge means extending transversely of the blank, means for mounting said plates on said supporting frame, and machine means for moving said plates longitudinally and inwardly.

8. In a machine of the character described, means for internally supporting a deformable tubular blank, a supporting frame having a plurality of longitudinally extending sides forming a tunnel enclosing said tubular blank, a plurality of series of blocks slidably supported on said frame, each series of blocks being supported on the inside of one side of said frame, a pair of fold plates hinged to each block, each of said plates being hinged to another plate, means to move said blocks toward one end of said frame and to move said fold plates progressively inward.

9. In a machine of the character described for folding a tubular blank into a folded bellows, a frame, means for internally yieldably supporting the interior of a tubular blank for folding operations, a plurality of series of folding members arranged about said tube, the folding members of each series being hinged together, a plurality of slide blocks mounted in said frame, alternate hinges between said members being pivoted to said blocks, means to move said blocks toward each other to move the alternate hinges toward each other and the other hinges moving toward each other and inwardly to form the tube into a bellows.

10. In a machine of the character described for folding a tubular blank into a folded bellows, a prism-shaped frame, means to provide an internal yieldable support during the folding operation for a tubular blank positioned in said prism-shaped frame, a series of blocks slidably mounted on each side face of said prism-shaped frame, a folding plate pivotally mounted on each slide block, said folding plates mounted on adjacent blocks of each series being hinged together, means to move said blocks toward each other and to move said folding plates toward each other and inwardly to fold said tubular blank into a polygonal bellows.

11. In a machine of the character described for folding a tubular blank into a folded bellows, a frame, means to provide an internal yieldable support for a tubular blank during folding operations, a plurality of series of folding members arranged about said tube, the folding members of each series being hinged together, a plurality of slide means mounted in said frame, alternate hinges between said members being connected to said slide means, means to move said slide means toward each other and to move the alternate hinges toward each other and the other hinges moving toward each other and inwardly to form the tube into a folded bellows.

12. In a machine of the character described for folding a tubular blank into a folded bellows, a prism-shaped frame, means to provide an internal yieldable support during the folding operations for a tubular blank positioned within said prism-shaped frame, a series of members slidably mounted on each side face of said prism-shaped frame, a folding plate supported on each member for pivotal movement relative to said frame, said folding plates supported on adjacent members of each series being hinged together, means to move

each member in each series toward each other and to move the folding plates toward each other and inwardly to fold said tubular blank into a polygonal bellows.

5 13. In a bellows folding machine, a frame, means supported on said frame to seal both ends of a tubular bellows blank, means to supply air under pressure through said sealing means to the interior of the tubular blank, a plurality of series of hinged fold plates having adjacent plates of a series hinged together, each series of hinged fold plates extending longitudinally along the machine axis between said means to seal both ends of the tubular blank, said plurality of series of hinged fold plates being transversely grouped about the machine axis, means supporting said plurality of series of hinged fold plates on said frame for movement inwardly toward the machine axis to form said tubular blank, and each fold plate of said series being hinged to the adjacent fold plate.

14. In a bellows folding machine, a frame, means supported on said frame to seal both ends of a tubular blank, means to supply air under pressure through said sealing means to the interior of the tubular blank, a plurality of series of hinged fold plates mounted on said frame about the machine axis, means to move said fold plates inwardly to form the tubular blank, and each of said fold plates being directly hinged to another fold plate.

15. In a machine of the character described for folding a tubular blank into a folded bellows, a supporting frame, means to internally support a tubular blank along the machine axis, supporting means slidably mounted on said supporting frame for guided straight line movement longitudinally along the machine axis, fold plates pivoted to said supporting means and supporting the tubular blank, means to move said support means longitudinally and to swing said plates toward each other and to swing said plates transversely inwardly toward the machine axis to form the tubular blank into a folded bellows.

45 16. In a machine of the character described, a frame, means to provide an internal support for a tubular blank during the folding operation, a plurality of series of folding members arranged about the tubular blank, the folding members of each series being hinged together, means to slidably support alternate hinges between said members on said frame, and means to move said alternate hinges toward each other and the intermediate hinges moving toward each other and inwardly to form the tubular blank into a folded bellows.

50 17. In a machine of the character described, a frame, means to support a tubular blank during the folding operation, a plurality of series of folding members arranged about the tubular blank, hinge means between the folding members of each series hinging said members together, means to slidably support alternate hinge means on said frame, and means to move said alternate hinges toward each other and the intermediate hinges moving toward each other and inwardly to form the tubular blank into a folded bellows.

60 18. In a machine of the character described, a supporting frame having an axis, fixed clamping means mounted on said supporting frame along the axis to secure one end of a tubular blank located along the axis, an axially movable sealing means mounted on said supporting frame and sealing the other end of the blank located along the axis, means to admit compressed air to the

11

interior of the blank through said fixed clamping means, a plurality of series of folding members having straight edges extending transversely of said axis, the straight edges of alternate series of said folding members engaging the blank spaced between and transversely angularly displaced from the straight edges of the intermediate series of folding members, means movably mounted on said supporting frame and supporting said members individually on the supporting frame for controlled movement inwardly in sequence commencing with the end folding member of one series and then the adjacent folding member of the other series until all the folding members move inwardly and means to move said folding members for said controlled movement.

19. In a machine of the character described, a supporting frame having an axis, means to provide support for the interior of a tubular blank located coaxially of said frame axis, folding means having tube engaging edges mounted on said supporting frame to form the tubular blank into a polygonal bellows consisting of a plurality of axially extending series of folding members grouped transversely about the tube, the edges of the folding members of each series being positioned transversely with respect to the axis and adjacent members of the respective series transversely angularly related, mounting means to mount said folding members individually on said frame for controlled longitudinal movement and for inward movement inwardly in a sequence starting with the end members of one series, then the axially adjacent members of the other series until all the members are moved inwardly.

20. In a machine of the character described, a supporting frame, means to supply compressed air to the interior of a tubular blank, means mounted on said supporting frame to seal one end of the blank, means movably mounted on said supporting frame to seal the other end of the blank, a plurality of series of trapezoidal folding members arranged in a first position in a generally tubular form about the tubular blank and movably mounted on said supporting frame, the bases of said trapezoidal members being movably interconnected in series for movement from said tubular form to a second position forming a surface having the shape of a collapsed polygonal bellows having trapezoidal sides, and means to move said members inwardly from said first position to said second position to form a surface having the shape of a collapsed polygonal bellows form to shape the blank into a polygonal bellows having trapezoidal sides.

21. In a machine of the character described, a supporting frame, means to supply compressed air to the interior of a tubular blank, fixed means mounted on said supporting frame to seal one end of the blank, movable means mounted on said supporting frame to seal the other end of the blank, a plurality of series of trapezoidal folding members arranged in a generally tubular form about the tubular blank, said plurality of series of trapezoidal folding members being movably mounted on said supporting frame and the trapezoidal folding members of each series being hinged together in series for movement from said tubular form to form a surface having the shape of a collapsed polygonal bellows, means to move alternate hinged portions of each series of said members inwardly and toward said fixed means to form a surface having the shape of a collapsed polygonal bellows form to shape the blank into a polygonal bellows.

12

22. In a machine of the character described, a supporting frame, means to internally support a deformable tube for forming a bellows, a plurality of pairs of folding plates surrounding the tube, said pairs of folding plates being hinged together at one point, means to movably support said pairs of folding plates at other points on said supporting frame, and direct machine actuating means to move said other points of said 5 pairs of plates together in sequence, with each successive pair of folding plates moving slower than the preceding pair of folding plates.

23. In a machine of the character described, a supporting frame having an axis, means to internally support a tubular blank coaxially along the frame axis, supporting means slidably mounted on said supporting frame for guided straight line movement longitudinally of said supporting frame along the blank and machine axis, fold plates mounted on said supporting means providing support for the tubular blank in one position, said fold plates and said support means being pivotally interconnected to move the fold plates inwardly in response to longitudinal movement of said support means, means to move said support means longitudinally to move said fold plates longitudinally and to swing said plates inwardly toward said axis of said supporting frame.

24. In a machine of the character described for folding a tubular blank into a folded bellows, a supporting frame having a longitudinal axis, means to internally support a tubular blank along the longitudinal axis, a plurality of fold plates arranged in a generally tubular form positioned coaxially with the axis of said frame and around the tubular blank and providing an external support for the tubular blank, each of said fold plates having pivot means to slidably and pivotally support said fold plates on said supporting frame, means interconnecting said plates to move said plates longitudinally along the axis of the frame and including means responsive to the longitudinal movement of said fold plates to move said plates toward each other and inwardly toward the machine axis to form the tubular blank into a folded bellows.

25. In a machine of the character described, a supporting frame having a longitudinal axis, means to supply compressed air to the interior of a tubular blank located coaxial with said axis, a fixed seal mounted on said supporting frame to close one end of the blank, a movable seal mounted for axial movement on said supporting frame to close the other end of the tubular blank, folding means mounted on said supporting frame to form the tubular blank into a polygonal bellows consisting of a plurality of axially extending series of folding members arranged longitudinally along the axis of the frame about the tubular blank, each of said folding members extending transversely, the transversely adjacent folding members being at an angle to each other, the folding members of each series being positioned between the members of the adjacent series, means longitudinally movable on said supporting frame, and said folding members being pivotally mounted on said longitudinally movable means for longitudinal movement along said axis and movement transversely toward said axis.

26. In a machine of the character described, a supporting frame having a longitudinal axis, means to supply compressed air to the interior of a tubular blank located coaxially of the axis, means mounted on the axis of said supporting frame to close one end of the blank, means mount-

75

ed on the axis of said supporting frame to close the other end of the blank, folding means mounted on said supporting frame to form the tubular blank into a polygonal bellows consisting of a plurality of axially extending series of folding members, each of said series of folding members extending along the frame axis and said plurality of series of folding members arranged transversely in a group about the blank located along the frame axis, each of said folding members 10 extending transversely, the transversely adjacent folding members being at an angle to each other, movable means interconnecting said folding members mounted on said frame to allow controlled movement of said folding members in- 15

wardly toward the frame axis in a sequence, said sequence including first moving the end members, second moving the axially adjacent members and then moving the next axially adjacent members, and means to move said folding members for said controlled movement.
